United States Patent Office

Des. 186,520
Patented Nov. 3, 1959

186,520

TABLE LEG OR THE LIKE

Robert I. Anderson, Muskegon, Mich., and David Chapman, Chicago, Ill., assignors to The Brunswick-Balke-Collender Company, Chicago, Ill., a corporation of Delaware

Application November 28, 1958, Serial No. 53,546

Term of patent 14 years

(Cl. D33—14)

Fig. 1 is a perspective view in elevation of a table leg showing our design;

Fig. 2 is a side elevational view thereof; and

Fig. 3 is a top plan view thereof.

The dominant features of our design reside in those portions shown in full lines on the drawing.

We claim:

The ornamental design for a table leg or the like, as shown and described.
